UNITED STATES PATENT OFFICE

2,571,215

FASTENER FOR SLIDING DOORS OF
RAILWAY CARSGeorge E. Dath, Mokena, Ill., assignor to W. H.
Miner, Inc., Chicago, Ill., a corporation of Dela-
ware

Application October 8, 1947, Serial No. 778,532

1 Claim. (Cl. 20—23)

1

This invention relates to improvements in fasteners for sliding doors, and more particularly for doors of this character supported for movement into and out of the door opening by swinging crank members rotatably supported on carrier means slidably guided for movement lengthwise of the car.

One object of the invention is to provide a sliding door construction for railway cars, comprising a rotary crank member swingingly supporting the door for in and out movement, fixed cam means with which the crank member is engageable during sliding movement of the door to closed position, to move the leading end of the door into the door opening, and a projecting cam lug on the leading end of the door engageable with the fixed keeper to wedge the door tightly shut, wherein the keepers and the cam means are formed on a single one piece bracket secured to the walls of the car, and the keeper engaging cam lug is formed on a bracket secured to the door, which bracket also serves as supporting bearing means for the crank member, thereby positively assuring proper relative positioning of the crank member, cam means, keeper and keeper engaging lug with respect to each other to prevent failure of the mechanism to function properly, which might otherwise occur due to accidental mislocation of these parts with respect to each other.

Other objects of the invention will more clearly appear from the description and claim herein-after following.

In the accompanying drawings forming a part of this specification, Figure 1 is a broken, elevational view of one of the side walls of a railway refrigerator car provided with a sliding door, illustrating my improvements in connection therewith. Figure 2 is a horizontal sectional view, corresponding substantially to the line 2—2 of Figure 1. Figure 3 is a view, similar to Figure 2, showing the door in dotted lines, slid to partly closed position parallel to the car wall, and in full lines, swung partly into the door opening.

In said drawings, 10 indicates the side wall of a car, which is provided with the usual door opening 11, closed by a sliding door 12. The door 12 is slideable along top and bottom tracks 13 and 14, being supported by the usual swinging crank members at the leading and rear ends of the same, the crank members at the leading end of the door only being shown, the same being indicated by 15—15. As shown, the crank members 15—15 are swingingly supported at their inner ends on the door, and swingingly connected at

2

their outer ends to the top and bottom tracks 13 and 14, the crank member 15 at the lower side of the door having its outer end journaled in a carrier 17 of well-known design, slideable on the lower track, and the crank member 15 at the top of the door having its outer end journaled in a roller 18, which is guided in the upper track 13, which is of channel-shaped cross section. As is well understood by those skilled in this art, the crank members 15—15 at the front end of the door, together with the crank members at the rear end thereof, not shown, are extended at right angles to the car wall when the door is in fully open position and hold the door in spaced parallel relation to the car wall during the major portion of movement of the door toward closed position, and are swung inwardly to move the door into the door opening during the final operation of closing the door.

20 In carrying out my invention, I provide broadly top and bottom brackets A—A secured to the car wall above and below the door opening, each bracket having a keeper B and a cam projection C thereon and formed rigid therewith, and top 25 and bottom bearing brackets D for the top and bottom crank members 15—15, each bearing bracket D having a projecting lug E thereon engageable with the keeper of the corresponding bracket A.

30 The brackets A—A are of similar design, but reversely arranged, that is, the upper bracket is inverted with respect to the lower one. Each bracket A is in the form of an L-shaped casting having a relatively long, horizontal arm 19 and 35 a relatively short, vertical arm 20, the arm 20 of the lower bracket upstanding from the arm 19 and that of the upper bracket depending from its arm 19. The top and bottom brackets A—A are secured to the wall of the car at respectively 40 the upper and lower corners of the forward end of the door opening, the long arms 19—19 extending along the top and bottom edges of the opening and the short arms 20—20 extending along the vertical edge at the front of said door opening.

45 The cam projection C of each bracket A is in the form of an elongated, outward, integral enlargement on the arm 19 in the path of movement of an extension 21 of the crank arm 22 of the corresponding crank member 15, the cam projection 50 of the upper arm being at the upper edge of the same at the right hand end portion thereof, and the cam projection of the lower arm being on the lower edge thereof at the right hand end of the same, as seen in Figure 1.

55 The keeper B of each bracket A is in the form

of an outwardly protruding socket on the arm 20, closely adjacent the corresponding corner of the door opening and is open at the right hand side, as seen in Figure 1. Each socket has the vertical outer wall 23 thereof inclined outwardly toward the door to provide an inner cam face with which the corresponding lug E is engageable.

The bearing bracket D in which the vertical shaft portion 24 of the corresponding crank member 15 is journaled is of the usual split type, comprising a back plate 25 and a cover plate 26. As shown in Figure 1, the lower bearing bracket D is secured to the door 12 at the lower left hand corner thereof and the upper bearing bracket D is secured to said door at the upper left hand corner.

The keeper engaging lug E of each bracket D is in the form of a projecting, laterally outwardly inclined finger, which is formed integral with the cover plate 26 of said bracket and is in alignment with the corresponding keeper B to engage with the latter and force the door closed.

As hereinbefore stated, the crank members 15—15 are normally in a position at right angles to the car wall when the door is open and hold the door in spaced parallel relation to said wall. In this right angular position of the crank members 15—15, the cam projections C—C of the top and bottom brackets A—A are in the paths of the ends 21—21 of the arms 20—20 of the crank members as the door is slid toward closed position along the tracks 13 and 14. Thus, as the door is slid toward closed position, the end 21 of each of the arms 20 encounters the corresponding cam projection C, as shown in dotted lines in Figure 3, and rides over this cam projection, as shown in full lines in said figure, to swing the crank member and carry the leading end of the door inwardly toward the side wall of the car and align the keeper engaging lug E of the corresponding bracket with its cooperating keeper B. As movement of the door to closed position is continued, the keeper engaging lug E enters the pocket of

the keeper and cams the leading end of the door tightly closed by wedging engagement with the inclined wall 23 of the keeper.

I claim:

In a door construction for a container having an opening in the wall thereof closed by a sliding door, the combination with top and bottom bearing brackets secured to the door; of top and bottom crank members for supporting the leading end of the door, each of said crank members including an arm swingingly supported at its outer end on a carrier which is slidable lengthwise of said wall, each of said arms having its inner end journaled in the corresponding bearing bracket; top and bottom L-shaped brackets secured to said wall at the forward end of said door opening, each of said L-shaped brackets having a long arm extending lengthwise of said opening and a short arm extending vertically along the vertical front edge of said opening; a cam projection on the horizontal arm of each L-shaped bracket, said cam projection being in the path of movement of the outer end of the arm of the corresponding crank member to be engaged by said arm to effect inward swinging movement of said arm as the door is being moved toward closed position; a socketed keeper on said vertical arm of each L-shaped bracket; and a projecting cam lug on each bearing bracket integral therewith, said projecting cam lugs of said top and bottom bearing brackets being engageable respectively with the top and bottom keepers to cam the door tightly closed.

GEORGE E. DATH.
